United States Patent Office.

JAMES W. SHUBERT AND NORVAL DOUGLAS, OF NEW HAVEN, CONNECTICUT.

Letters Patent No. 97,711, dated December 7, 1869.

IMPROVEMENT IN PLATES FOR HOLDING THE LIDS OF TRUNKS IN PLACE.

The Schedule referred to in these Letters Patent and making part of the same.

To all whom it may concern:

Be it known that we, JAMES W. SHUBERT and NORVAL DOUGLAS, of New Haven, in the county of New Haven, and in the State of Connecticut, have invented a certain new and useful Improvement in Plates for Holding the Lids of Trunks in Place; and do hereby declare that the following is a full, clear, and exact description thereof, reference being had to the accompanying drawings, and to the letters of reference marked thereon.

In the annexed drawings, forming part of this specification—

Figure 1 is a sectional view of the plates when closed together, and

Figure 2, a view of the upper plate.

The nature of our invention consists in providing the corners of trunks with plates, so that the lids may shut down and remain fixed, and not work one side or the other, as they are apt to do if not provided with some preventive.

To enable others skilled in the art to make and use our invention, we will proceed to describe its construction and operation.

On the upper front corners of the trunk, plates of any suitable kind of metal are securely fastened, which

plates are bent over the edges and sunk into them, to be exactly even.

On the top of these plates are holes bored to admit the corresponding tenons, on similar plates fastened on the corners of the lid.

In the annexed drawings—

A represents the plate fastened on the trunk.

B, the plate fastened on the lid.

C are the tenons on plate B, which fit into plate A.

When the lid is fastened down, the tenons C fit into the holes made for their reception, and prevent the lid from moving to one side or the other.

Having thus fully described our invention,

What we claim as new, and desire to secure by Letters Patent, is—

The plates A and B, fastened on the corners of trunks, and operating substantially as and for the purposes herein set forth.

In testimony that we claim the foregoing, we have hereunto set our hands, this 21st day of April, 1868.

JAMES W. SHUBERT.
NORVAL DOUGLAS.
